UNITED STATES PATENT OFFICE.

ROBERT R. WEAVER, OF COLUMBUS, OHIO, ASSIGNOR TO THE RALSTON STEEL CAR COMPANY, OF COLUMBUS, OHIO.

CAR-UNDERFRAME.

1,247,914.

Specification of Letters Patent. Patented Nov. 27, 1917.

Application filed March 11, 1916. Serial No. 83,590.

To all whom it may concern:

Be it known that I, ROBERT R. WEAVER, a citizen of the United States, and a resident of Columbus, in the county of Franklin and State of Ohio, have invented certain new and useful Improvements in Car-Underframes; and I do hereby declare the following to be a full, clear, and exact description of the invention, such as will enable others skilled in the art to which it appertains to make and use the same.

This invention relates to improvements in car underframes and more particularly to the construction of the cross bearers and the connection of the same with the center girder and side sills,—an object of the present invention being to provide a substantial cross bearer, the outer end of which shall have an extended connection with the side sill and still be in a plane below that of the top of the side sill and also below the plane of the top of the inner end of the cross bearer.

With this and other objects in view, the invention consists in certain novel features of construction, and combinations of parts as hereinafter set forth and pointed out in the claims.

In the accompanying drawings; Figure 1 is a sectional view showing an embodiment of my invention, and Fig. 2 is a fragmentary view taken at right angles to Fig. 1.

For the purposes of this case it will suffice to show and describe a single cross bearer and its connection with the center girder and side sill.

1 represents a center girder and 2 a side sill, the latter being shown in the drawing as being of channel form with its upper and lower flanges projecting inwardly.

My improved cross bearer 3 is preferably made of pressed steel of general channel form, having upper and lower flanges 4—5 and a vertical flange 6 at its inner end. The cross bearer has a general tapering shape with its larger end approximately equal to the space between the upper and lower flanges of the center girder,—said larger end of the girder being disposed between said upper and lower center girder flanges so that its top shall be below the plane of the top of the center girder, and the vertical flange 6 at the larger inner end of the cross bearer is disposed against the

web of the center girder so that it may be secured thereto.

The smaller outer end of the cross bearer enters between the inwardly projecting flanges of the side sill 2 and the web of this smaller outer end 7 of the cross bearer is extended upwardly as shown at 8 and the upper flange of the cross bearer is omitted from the major portion of said upward web extension. The extended outer end 7—8 of the cross bearer is secured to the web of the side sill by means of an angle iron 9.

It will be observed that the connection of the cross bearer to the side sill is below the upper flanged edge of the side sill; that the top of the enlarged inner end of the cross bearer is below the plane of the top of the center girder and above the plane of the top flange at the outer end of said cross bearer, and also above the top of the extended web at said outer end of the cross bearer, and that the top of the side sill is slightly above the plane of the top of the center girder and coincident with the floor line.

In the drawing, I have shown a cover plate 10 which extends over the center girder and partly over the cross bearer, and I have also shown a Z-beam 11 for supporting the floor intermediate the ends of the cross bearer.

Having fully described my invention what I claim as new and desire to secure by Letters-Patent, is:—

1. The combination with a center girder and a side sill, of a cross bearer having a general tapering shape with its wider end secured to the center girder, said cross bearer having upper and lower longitudinal flanges, a portion of the upper flange being omitted at the smaller end of the cross bearer and the web of said smaller end being extended above the flanged edge thereof, said extended web portion being confined between the upper and lower edges of the side sill, and an angle member secured to said extended web portion and to the side sill wholly between the upper and lower edges of the latter.

2. The combination with a center girder, and a side sill having inwardly projecting flanges at its respective edges, of a cross bearer having a general tapering form and provided with upper and lower lateral flanges, the smaller end of the cross bearer

having a portion of its upper flange removed and having its web portion extended upwardly and disposed between and spaced from the upper and lower flanges of the side sill, means for securing said smaller end of the cross bearer to the side sill below the upper flange and above the lower flange thereof, and the top of the enlarged end of the cross bearer being in a plane above that

of the top of the extended web at the smaller end of said cross bearer.

In testimony whereof, I have signed this specification in the presence of two subscribing witnesses.

ROBERT R. WEAVER.
